UNITED STATES PATENT OFFICE.

FRANCIS MARION VANDERVOORT, OF FREDONIA, KANSAS.

FRONT-DRIVE TRACTOR.

1,091,720.

Specification of Letters Patent. Patented Mar. 31, 1914.

Application filed December 27, 1912. Serial No. 738,817.

To all whom it may concern:

Be it known that I, FRANCIS MARION VANDERVOORT, citizen of the United States, residing at Fredonia, in the county of Wilson and State of Kansas, have invented certain new and useful Improvements in Front-Drive Tractors, of which the following is a specification.

The present invention relates to a front drive tractor, and has for its object to provide a device of this character which embodies novel features of construction whereby the tractor may be turned around as sharply as desired, thereby enabling it to be advantageously employed for drawing plows or harvesting machinery, since it may be run clear up into the corners of the field and then turned sharply around, substantially the same as would be possible with 20 horses.

A further object of the invention is to provide a tractor which is strong and compact in its construction, which enables practically all of the weight to be placed upon the drive wheel, and which can be easily steered and controlled by the driver.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawing, in which:—

Figure 1 is a top plan view of a front drive tractor constructed in accordance with the invention, the drive or traction wheel 40 being shown in section and parts being broken away to more clearly illustrate the invention. Fig. 2 is a side elevation of the front drive tractor, parts being broken away and shown in section. Fig. 3 is a similar 45 view looking at the machine from the opposite side thereof. Fig. 4 is an enlarged detail sectional view of the clutch mechanism which controls the steering device, and Fig. 5 is a detail view of a portion of the gearing 50 for steering the machine.

Corresponding and like parts are referred to in the following description and indicated in all the views of the drawings by the same reference characters.

Specifically describing the present embodiment of the invention, the numeral 1

designates the main frame of the machine, the said frame being substantially circular in shape and being provided at the rear thereof with an extension 1^a upon which the 60 axle 2 is mounted. This axle 2 is provided at the ends thereof with the usual supporting wheels 3, and the extension 1^a of the frame is formed with a coupling member 4^a by means of which the tractor can be readily 65 connected to a plow, piece of farming machinery or the like. A horizontal frame 4 is mounted upon the main frame 1 to turn about a vertical axis, the said horizontal frame carrying the engine 5 and traction 70 wheel 6. In the present instance the circular portion of the main frame 1 is formed of channel iron so as to provide a track upon the interior thereof, and the horizontal frame 4 is provided at the corners thereof 75 with the brackets 7 upon which guide wheels 8 are journaled, the said guide wheels engaging the channeled track of the circular frame of the tractor.

The traction wheel 6 surrounds the engine 5 and is provided at the middle thereof with an inwardly facing annular rack 9, and at each edge thereof with an inwardly facing track or guideway 10. The two annular tracks 10 are engaged by guide rollers 11 arranged at opposite sides of the horizontal frame 4. In the present instance there are three of these guide rollers 11 on each side of the tractor 6, two of the said guide wheels being journaled upon brackets 90 12 which project downwardly from the frame 4, while the third and upper guide wheel of each set is journaled upon a bracket 13 which projects upwardly from the frame 4. With these guide wheels 11 95 engaging the peripheral tracks 10 at each edge of the traction wheel 6 it will be obvious that the said traction wheel is perfectly free to rotate about a horizontal axis although it is held securely against lateral 100 displacement.

The annular rack 9 upon the interior of the traction wheel 6 is engaged by a drive pinion 14 upon a shaft 15 which is journaled in bearings 16 upon a bracket 17 which is 105 rigid with the horizontal frame 4. One end of the shaft 15 is provided with a beveled gear wheel 18 which meshes with a pair of beveled gear wheels 19 loose upon an inclined shaft 20. This inclined shaft 20 is 110 journaled within suitable bearings 21 and is connected by the bevel gearing 22 to a

countershaft 23 running parallel to the engine shaft 24 and connected thereto by the usual speed changing gearing 25. The outer end of the countershaft 23 is provided with 5 a drive pulley 26 from which power may be taken from the machine for driving any desired mechanism.

The speed changing gear 25 is controlled by a lever 27 which is mounted upon the 10 operator's platform 28. This operator's platform 28 is arranged at the rear of the traction wheel 6 and is supported from the horizontal frame 4 by means of suitable brackets 29. It will also be observed that 15 the operator's platform 28 is elevated above the rear wheels 3 so as to swing over the same as the traction wheel is turned to the right or to the left. A clutch member 30 which has a feather and spline connection 20 with the shaft 20 is arranged between the two gear wheels 19 and is adapted to be moved into a positive engagement with either of the said gear wheels by means of a lever 32, the said lever being connected 25 to the clutch member by a link 33. Owing to the arrangement of the various gear wheels, it will be obvious that when the clutch member 30 is thrown into engagement with one of the gear wheels 19, the traction 30 wheel will be driven in one direction, while when the clutch member is moved into engagement with the opposite gear wheel the traction wheel will be driven in the reverse direction, one of the gear wheels 19 being 35 locked with the shaft 20 while the other gear wheel is loose upon the said shaft.

It is also contemplated to provide means for steering the machine, and for this purpose the exterior of the circular main 40 frame 1 is provided with an annular rack 34, the said rack being engaged by a pinion 35 rigid with a sleeve 35^a which is loose upon a short vertical shaft 36, said shaft 36 being carried by a bracket 37 of the horizontal frame 4. A pin 36^a at the lower end of the stub shaft 36 serves to hold the sleeve 35^a in position upon the said shaft 36. The upper end of the vertical sleeve 35^a is provided with a worm gear 38 which meshes 45 with a worm 39 upon a horizontal shaft 40, the said horizontal shaft being journaled within suitable bearings 41 and being provided at the end thereof with a bevel gear wheel 42. This bevel gear 42 meshes with 50 a pair of similar bevel gear wheels 43 which are loose upon the engine shaft. A suitable clutch member 44 which has a feather and spline connection 45 with the engine shaft is mounted between the two bevel gear 55 wheels 43 and is adapted to be moved into a frictional engagement with either of the said gear wheels, or to be locked in an intermediate and inoperative position. This clutch member 44 has an operative connection 60 with the hand lever 46 through the

medium of the link 47 and lever 48. When the clutch member 44 is in an intermediate position, both of the bevel gear wheels 43 will be loose upon the engine shaft, and by moving the clutch member to lock either of the said gear wheels with the shaft, the steering shaft 40 may be rotated in either direction. When the steering shaft 40 is rotated, the pinion 35 is caused to travel around the circular main frame 1 upon the rack 34, the horizontal frame 4 and traction wheel 6 being thus turned about a vertical axis so as to steer the machine. When the pinion 35 turns in one direction, the traction wheel 6 is turned to one side, while when the pinion 35 is turned in the opposite direction, the traction wheel 6 is turned to the other side. Very sharp turns can be made, and if desired the traction wheel 6 can be turned entirely around within the circular frame 1. This is of very great importance where the tractor is employed for farm purposes, since in order to adapt the tractor for use in connection with plows or the like, it is necessary that very sharp and frequent turns be possible. Furthermore, substantially all of the driving mechanism is arranged within the traction wheel 6 so as to center the weight at the desired point. 70 75 80 85 90

Having thus described the invention, what I claim as new and desire to secure by Letters Patent, is:—

1. A tractor including a main frame, a horizontal frame adapted to turn about a vertical axis, the said main frame being formed with a curved track which is concentric with the vertical axis of the horizontal frame, guide means upon the horizontal frame engaging the track of the main frame, a hollow traction wheel through which the horizontal frame extends, said traction wheel being provided upon opposite sides thereof with annular guide ways and being also provided with an interior annular rack, rollers carried by the horizontal frame and engaging the said guide ways of the traction wheel to admit of the traction wheel turning freely about a horizontal axis, a pinion carried by the horizontal frame and meshing with the interior rack of the traction wheel, and means for driving the pinion. 100 105 110 115 120

2. A tractor including a main frame, a horizontal frame adapted to turn about a vertical axis, the said main frame being formed with a curved track which is concentric with the vertical axis of the horizontal frame, guide means upon the horizontal frame engaging the track of the main frame, a hollow traction wheel through which the horizontal frame extends, said traction wheel being provided upon the interior thereof with a pair of annular guideways, rollers carried by the horizontal frame and engaging the said guideways of the traction wheel to admit of the traction wheel turn- 125 130

ing freely about a horizontal axis, an engine mounted upon the horizontal frame and arranged within the hollow traction wheel, and gearing between the engine and traction wheel.

3. A tractor including a main frame, a horizontal frame adapted to turn about a vertical axis, said main frame being formed with a curved track which is concentric with the vertical axis of the horizontal frame, guide means upon the horizontal frame for engaging the track of the main frame, a hollow traction wheel through which the horizontal frame extends, said traction wheel being provided upon the interior thereof with a pair of annular guideways, guide rollers carried by the horizontal frame and engaging the said guideways to admit of the traction wheel turning freely about a horizontal axis, an annular rack upon the traction wheel, a bearing carried by the horizontal frame, a shaft mounted in the bearing, a pinion carried by the shaft and engaging the rack of the hollow traction wheel, an engine mounted upon the horizontal frame and arranged within the hollow traction wheel, and gearing between the engine and the said shaft.

4. A tractor including a main frame formed with a circular track, a horizontal frame arranged within the circular track and adapted to turn about a vertical axis, guide members carried by the horizontal frame and engaging the said circular track, a hollow traction wheel through which the horizontal frame extends, said traction wheel being provided at opposite edges thereof with interior annular guideways, brackets projecting from the horizontal frame, guide rollers upon the brackets for engaging the annular guideways to admit of the traction wheel turning freely about a horizontal axis, an annular rack upon the traction wheel, a pinion engaging the rack,

bearings carried by the horizontal frame, a shaft journaled within the bearings and carrying the pinion, a second set of bearings upon the horizontal frame, a second shaft journaled in the said bearings, reversible gearing between the said second shaft and the first shaft, an engine upon the main frame, and changeable speed gearing between the engine and the second shaft.

5. A tractor including a main frame formed with a horizontally disposed circular track, a horizontal frame arranged within the circular track and adapted to turn about a vertical axis, guide members carried by the horizontal frame and engaging the circular track, a hollow traction wheel through which the horizontal frame extends, said hollow traction wheel being provided at opposite edges thereof with interior annular guideways, brackets projecting from the horizontal frame, rollers carried by the brackets and engaging the annular guideways of the traction wheel so that the said traction wheel is adapted to turn freely about a horizontal axis, an engine mounted upon the horizontal frame and arranged within the hollow traction wheel, a bearing carried by the horizontal frame, an interior annular rack at the middle of the hollow traction wheel, a shaft journaled in the said bearing, a pinion carried by the shaft and engaging the rack, a second set of bearings carried by the horizontal frame, a second shaft journaled in the said second set of bearings, reversible gearing between the second shaft and the first shaft, and gearing between the second shaft and the engine.

In testimony whereof I affix my signature in presence of two witnesses.
